United States Patent Office

THOMAS CATO McKEEN, OF IRVINGTON, NEW JERSEY, ASSIGNOR TO THE
NEW YORK SUBMARINE COMPANY.

Letters Patent No. 65,760, dated June 11, 1867.

IMPROVED DIVING APPARATUS.

The Schedule referred to in these Letters Patent and making part of the same.

TO ALL WHOM IT MAY CONCERN:

Be it known that I, THOMAS CATO McKEEN, of Irvington, in the county of Essex, State of New Jersey, United States of America, have invented new and useful improvements in Diving Apparatus for submarine purposes; and I do hereby declare that the following is a full, true, and exact description of my said improvements and apparatus, reference being had to the accompanying drawings, making a part of this my specification, in which drawings—

Figure I represents a side elevation of the apparatus as worn upon the diver, with the air-reservoir and buoys worn upon the outside of the dress.

Figure II represents the same without the air-reservoir, or outer rubber or other covering of the dress, and shows the hoops or rings with which the apparatus is provided to protect the diver from the pressure of the water at great depths.

Figure III represents a side elevation of the apparatus as worn by the diver, with the air-reservoir inside of the dress, and without the rubber or other covering of the dress.

Figure IV represents a rear elevation of the pantaloons as provided with hoops or rings for protection at great depths.

Figure V represents a side view of the chest or body-armor, worn below the helmet and above the pantaloons. The water-proof clothing or dress would cover this.

In all the figures the same letters represent the same parts.

The object of this invention is to afford a diver improved methods of carrying with him a supply of fresh air sufficient for his breathing for several hours, and improved buoys which he can inflate at pleasure so that he can rise to the surface when he wishes without the aid of other persons, and also to protect, by use of hoops or rings in his dress, his body and limbs from the pressure and impact of the water when at considerable depths.

To enable those skilled in the art to make and use my invention, I now proceed to describe the manner of constructing and using the same.

A represents an ordinary diving-dress made of India rubber or other water-proof material in the ordinary form. B is the helmet, made of sheet copper or other suitable material in the ordinary way. C are nuts for fastening clamps, joining the helmet and the dress. D is the reservoir for compressed air, made of sheet copper, or other suitable material, in the shape of a knapsack, or any other desirable form or shape, provided with straps so that it can be secured to the back or shoulders and carried conveniently by the diver, as shown in the Fig. I, or made in a tubular air-chamber or chambers, E, forming a body-armor, and worn around the chest and body inside of the dress, as shown in Fig. III; whichever way it is made and worn always leaving the diver's hands and arms free to work and (as free as possible) his body to bend. The reservoir must be made sufficiently strong to hold a large quantity of air compressed into about one-sixtieth, or a still smaller fraction, of its original or ordinary bulk, and should be filled with compressed air by means of a force-pump before the diver puts it on. It may be all one chamber or divided into compartments, one for the air for the use of the diver in breathing, and one for that for his use in inflating his buoys and remounting to the surface.

Although Fig. III displays the reservoir made in a tubular air-chamber or chambers when it is worn around the body within the dress, yet, when it is so worn either within or without the dress, the air-reservoir may be made of tubes in sections, which shall be so operated that they shall be successively exhausted of air, or they may be arranged as one long tube wound in a coil, or the reservoir may be a complete chamber of smooth, flat sides, or any other form of construction may be adopted.

When the reservoir is worn around the chest or body, it also acts as the chest or body-armor, and renders the armor displayed in Fig. V unnecessary.

The air-reservoir is provided with a pipe, F, which extends to the interior of the dress near the lower part of the helmet. A faucet, G, opens or closes the communication between the air-reservoir and the interior of the dress, and by opening the faucet gradually the diver is enabled to obtain a proper supply of air until the air-reservoir is exhausted, or until he desires to rise to the surface, for the compressed air immediately rushes through the pipe F and seeks its natural dimensions. A perforated plate or tube, like that marked I, made of metal or other material, may be used for spreading or distributing the air after it enters the helmet. A small

pipe, provided with a valve, H, opening upwards in the top of the helmet, and which pipe may be either of metal or of some flexible material, carries off the deteriorated air. The helmet may have simply the discharge air-valve without the pipe, though I prefer to use the short pipe.

For the purpose of protecting the lower limbs and the body of the diver from undue pressure and impact of the water at great depths, I provide the legs and body of the dress with a series of rings or hoops, shown in side elevation in Fig. III, and rear elevation in Fig. IV, and numbered 1, 2, 3, 4, &c. These rings or hoops are made of metal, and may be hollow, like tubes, or not. They are graduated in size to correspond with the different parts of the dress, and they are inserted at intervals within the rubber or other materials constituting the dress, or attached within it, so that they will keep the dress free of the body and limbs, and relieve them of the direct pressure of the water, and at the same time permit the motion and bending of the body and limbs in any direction.

J is one of the buoys fitted under the arm, and laced to a similar buoy on the other side of the diver by the lacings K before the chest and behind the back. These bags or buoys are made of India rubber, or of layers of canvas covered with a preparation of rubber or of some other flexible or suitable material, and may be covered with a cordage netting of slightly less diameter both ways than the buoy proper, so as to relieve the buoy of strain when inflated, and prevent its bursting. These buoys communicate with the interior of the air-reservoir D by a pipe, L, which may be opened or closed by a faucet, M, and which, if the reservoir is divided into compartments, would enter that compartment intended for the air for inflating the buoys. When the diver is in the water, if the buoys are inflated he will stand head and shoulders out of the water, when the mouth-piece of his helmet may be opened, and he can converse with those on board his boat or vessel, or ashore. The buoys are provided with an exhaust pipe, N, which has a faucet, O, by opening which the air in the buoys is allowed to escape, the arms being used to press it out of the buoys, if necessary, when the diver will gradually sink. For the sake of convenience in reaching the faucet O I prefer carrying the escape pipe N inside of the helmet, and placing the faucet O in front of the helmet as shown in Fig. I.

When the diver, being submerged, wishes to rise to the surface, he fills his buoys by turning the faucet M, the air rushes into and inflates the buoys, and they bear him up. In this method not only can the diver rise to the surface, but he can also bring articles of considerable weight with him. He can also, by graduating the supply of air in the buoys, and their consequent inflation, suspend himself at any required depth in the water without either touching the bottom or rising to the surface.

It is thus seen that by means of my apparatus a diver is enabled to descend to the bottom, move about on the same, and to ascend to the surface of the water, or suspend himself at any required depth in the water without the assistance of any other person, so that he has the control of all his movements, and so that the danger of suffocation by an interruption or accident to the connections between the diver and any person above is avoided. The diver can thus work with much more safety than with any other diving apparatus, and he can apply his whole energy to the work to be performed.

What I claim as new, and desire to secure by Letters Patent, is—

The use and application of hoops or rings to the diving-dress, constructed and operating in the manner and for the purposes described.

T. CATO McKEEN.
